UNITED STATES PATENT OFFICE.

GEORGE J. CAMPBELL, OF POUGHKEEPSIE, NEW YORK, ASSIGNOR TO LANE BROTHERS COMPANY, OF POUGHKEEPSIE, NEW YORK, A JOINT-STOCK ASSOCIATION OF NEW YORK.

LIFTING-JACK.

1,376,511.

Specification of Letters Patent.

Patented May 3, 1921.

Application filed December 7, 1920. Serial No. 428,911.

To all whom it may concern:

Be it known that I, GEORGE J. CAMPBELL, a citizen of the United States, and a resident of Poughkeepsie, New York, have invented 5 certain new and useful Improvements in Lifting-Jacks, of which the following is a specification.

My present invention relates to improvements in lifting jacks of the step up and step 10 down type and more particularly to the form of jack shown in Letters Patent of the United States, No. 1,181,395, granted to George Lane, on the 2nd day of May, 1916, said patent disclosing a jack in which the 15 raising or lowering of the jack is controlled by a shifting of the handle bar in the socket of the actuating lever. In the said patented construction, the handle bar was positively locked or held in the socket by a dog or pawl 20 which, while permitting the relative movement necessary to reverse the jack, yet prevented its complete removal, whereby the handle bar was capable of being used for the purpose of placing the jack in operative 25 position and effecting its subsequent removal; and in order to completely remove the handle, it was necessary to manipulate the dog or pawl.

The present invention aims to provide a 30 construction in which the handle will be so held in the socket member as to enable the relative shifting movement to be imparted thereto while so held to effect the reversal of the jack and in which the handle bar will 35 be retained in the socket with sufficient permanency to enable the jack to be manipulated by the use of the handle and yet enable the handle bar to be removed from the socket by a direct pull, thus avoiding the necessity 40 of any manipulation of a separate retaining pawl.

To this end the invention includes the novel features of construction and arrangement and combination of parts hereinafter 45 described, the said invention being defined by the claims appended hereto.

Several forms of my invention are illustrated in the accompanying drawings, in which—

50 Figure 1 is a side elevation with parts broken away showing a sufficient portion of a jack to illustrate the invention.

Fig. 2 is a sectional detail,

Fig. 3 is a view similar to Fig. 2, showing a different position of the handle bar in the 55 socket.

Fig. 4 is a perspective view of the end of the handle bar.

Fig. 5 is a view similar to Fig. 4 but showing a modified form of spring.

Fig. 6 is a longitudinal sectional view 60 through the handle bar of Fig. 5 and a socket lever or member modified to coact therewith.

Fig. 7 is a section on line 7—7 of Fig. 6 65 looking in the direction of the arrow.

Fig. 8 is a perspective view showing a modified form of spring attachment.

Fig. 9 is a sectional elevation of a further 70 modification, and Figs. 10 and 11 are detail views illustrating a rotary handle.

Referring by reference characters to these drawings, the numeral 2 designates the standard and 3 the lifting bar guided therein, being actuated by the lifting or lowering 75 pawl 5 coöperating with a holding or retaining pawl 4, the former being pivoted on the actuating lever or member 6, and the latter on a fixed pivot carried by the standard.

The pawls are shown as connected by the 80 close coiled springs 13 and 14 to the bell crank levers 11 and 12, pivotally supported from the standard and being under the tension of the common spring C.

Action of the bell crank levers and pawls 85 will be readily understood by those skilled in the art, it being understood that when the inner ends of the shoulders 11^b and 12^b are unobstructed, the operation of the lever or actuating member 6 effects an upward step 90 by step movement of the lifting bar, while when the movement of said ends or shoulders is alternately obstructed, a step by step lowering of the bar takes place, the obstruction being accomplished by the spring-pressed 95 cross bar 21. The handle bar is shown at 7 and it will be understood that when this handle bar is pushed into the socket to its furthest extent, as shown in Fig. 3, the obstructing cross bar 21 will be carried forward 100 against the tension of its spring 22 into the position shown in dotted lines in Fig. 1, where it will be out of position to contact with the shoulders 11^b and 12^b. In this position of the parts, the up and down movement of the handle bar will raise the lifting 105

bar 3 in a manner well understood by those familiar with this type of jack. However, when the handle bar is shifted backwardly to a slight extent (as indicated in Fig. 2), 5 while held in the socket, the contact bar 21 is allowed to assume the position indicated in full lines in Fig. 1 under the action of its spring 22 whereby it will contact alternately with the shoulders 11^b and 12^b of the bell 10 cranks and so control the action of the pawls as to effect the step by step lowering of the jack.

One form of means by which the handle bar 7 is held in the socket so as to be shiftable to either of the two positions required, 15 in a manner to enable it to be used for placing and removing the jack and yet to be removable from the socket member by a direct pull, is shown in Figs. 1 to 4 inclusive. In 20 this form I interpose between the handle bar and the wall of the socket a friction member, preferably in the form of a spring 8 carried by the side of the handle lever, to which it is secured by suitable means, such as a rivet 9, 25 the free portion of the spring tending to press against the wall of the socket. This spring exerts sufficient pressure against the wall of the socket to retain the handle bar against accidental displacement or removal 30 in the manipulation of the jack, as, for instance, the placing of the jack under the axle of the car or its removal or during the up and down movement of the handle bar. It will be obvious that with spring friction means 35 such as described, the handle bar may be shifted in the socket to either of the two positions desired to control the vertical movement of the lifting bar, merely by the application of sufficient force to overcome the 40 friction of the spring, and similarly the handle bar may be completely removed from the socket by an additional direct line pull. I prefer to recess the handle bar as shown, to receive the spring, the bend projecting beyond 45 the walls of the recess.

In Fig. 5, I have shown the frictional retaining spring 8^a as designed to retard the movement of the handle bar in its socket when the lowering position is reached, while 50 yet being capable of automatic yielding under further and harder pull to permit the removal of the handle bar. This is accomplished by providing the spring with a bend *a* which cooperates with a rib 6^a on the wall 55 of the socket, this bend terminating at the outer end in a notch or recess *a'* with an inclined shoulder *a''* which is more abrupt than the opposite wall of said recess *a'*. The spring would yield with comparative ease 60 under the action of the rib or flange 6^a under a push or pull to shift the handle bar in the socket but when the handle bar is pulled outwardly from its innermost or lifting position the engagement of the rib or flange in the 65 spring recess *a'* will automatically stop fur-

ther movement of the handle at lowering position, although the handle may thereafter be removed by a harder direct pull.

It is obvious that the spring may be set into a recess in the side of the handle bar, as 70 shown in Figs. 4 and 5, or that it may be secured to the unrecessed face of the handle bar, as shown at 8^b in Fig. 8, in which event the socket would have to be correspondingly shaped. 75

Instead of placing the spring at the side of the handle bar as in the preceding forms, I may place it on the bottom of the socket member, as shown at 8^c and provide it with a bend *a* of reverse V-shape forming in effect 80 a shoulder or lug which projects through an opening in the socket member and cooperates with reversed V-shaped notches 7^c in the lower edge of the handle bar, as shown in Fig. 9, the inclined walls of which permit the 85 handle bar to be shifted in the socket to either of two determined positions or pulled completely out by a direct push or pull.

It will be understood that this invention pertains only to the movement, holding 90 and control of the jack handle in the lever socket, and while illustrated in connection with jack mechanism as shown in Patent #1181395, it is equally applicable to any other mechanism where reversal of the jack 95 is effected by shifting the position of the handle in the socket.

Instead of shifting the handle bar longitudinally in the socket to effect the control or reversal of the jack they may be 100 accomplished by a rotary movement as illustrated in Figs. 10 and 11, in which the handle 7^r is mounted to have a rotary movement in the socket 6^r which is of cylindrical shape to receive the cylindrical end 105 of the handle bar. The handle bar has a substantially V-shaped notch *a* in its end in which the member 21 lies in one position of the handle bar (the lowering position, for example) while a substantially quarter 110 turn of the handle bar causes member 21 to be forced out of the notch or recess by the cam action of the walls, thus shifting said member 21 to raising position.

The handle bar has a transversely disposed elongated slot 7^r which is engaged by a wedge shaped member or dog 18 carried by the spring 8^r and projecting through an opening in the socket member, said spring forcing the dog into the slot 120 and the parts are preferably so constructed and arranged that the inclined faces of the dog frictionally engage the edges or walls of the slot, so that the handle bar is frictionally retained in either position to which it may be adjusted, though turnable under the application of sufficient pressure to overcome the friction. 125

When it is desired to remove the handle a direct outward pull of sufficient force 130

will cause the dog to be forced outward by reason of its inclined face, thus permitting ready removal of the handle.

I claim:

5 1. A lifting jack comprising a standard, a lifting bar movably guided thereby, mechanism for moving the bar upward and downward, said mechanism including a rocking member having a socket, a hand lever having an end detachably held in said socket to have relative movement therein while so held, means controlled by said relative movement of the hand lever to determine whether said mechanism shall raise 10 or lower the lifting bar, and frictional restraining means interposed between the handle bar and the socket.

2. A lifting jack comprising a standard, a lifting bar movably guided thereby, mechanism for moving the bar upward and downward, said mechanism including a rocking member having a socket, a hand lever having an end detachably held in said socket to have relative movement therein 25 while so held, means controlled by said relative movement of the hand lever to determine whether said mechanism shall raise or lower the lifting bar, said socket and said hand lever having frictional engaging 30 means comprising a spring carried by one part and frictionally engaging the other part.

3. A lifting jack comprising a standard, a lifting bar movably guided thereby, mechanism for moving the bar upward and downward, said mechanism including a 35

rocking member having a socket, a hand lever having an end detachably held in said socket to have relative movement therein while so held, means controlled by said relative movement of the hand lever to determine whether said mechanism shall raise or lower the lifting bar, a leaf spring having one end secured to one face of the actuating handle and having a bend or swell 40 terminating toward the free end of the spring in an inclined shoulder, and a rib or projection on the socket wall coöperating with said bend and shoulder.

4. In a lifting and lowering jack in 50 which the control of the jack is effected by the position of the handle bar in the socket of the actuating member, means for releasably holding and positioning the handle bar in the socket member comprising a leaf 55 spring carried by one of said parts and having a curved portion or bend terminating at its base at one end in an inclined shoulder, and a rib on the other part coöperating with said bend and inclined shoulder.

5. In a lifting and lowering jack in 60 which the control of the jack is effected by the position of the handle bar in the socket of the actuating member, means for releasably holding and positioning the handle bar 65 in the socket member comprising a leaf spring carried by one of said parts, and having a bend coöperating with a shoulder on the other part.

In testimony whereof I affix my signature. 70

GEORGE J. CAMPBELL.
